UNITED STATES PATENT OFFICE.

FRANK R. HAHN, OF DECATUR, ILLINOIS.

BUILDING CONSTRUCTION.

Application filed May 23, 1918, Serial No. 236,080. Renewed May 13, 1924.

To all whom it may concern:

Be it known that I, FRANK R. HAHN, a citizen of the United States, a resident of Decatur, in the county of Macon and State 5 of Illinois, have invented new and useful Improvements in Building Constructions, of which the following is a specification.

My invention relates to improvements in building construction, and particularly to 10 that type of construction wherein the wall is composed of a plurality of pre-cast slabs or units which are supported by supporting posts or columns.

The principal object of this invention is 15 the provision of such a construction, whereby a wall may be quickly erected and securely supported and held together.

Another purpose of this invention is the adaptation of this idea to both single and 20 double wall construction.

To the accomplishment of the foregoing and such other objects as may hereinafter appear, my invention consists in the combination, construction and arrangement of 25 parts hereinafter described and then sought to be defined in the appended claims, reference being had to the accompanying drawings forming a part hereof, and which show merely for the purpose of illustrative disclosure, a preferred embodiment of my invention, it being understood that various 30 changes may be made in practice within the scope of the claims without digressing from my inventive idea.

35 In the drawings,

Figure 1 is a top plan view of a portion of a wall constructed to embody my invention, the supporting post being shown in section to facilitate the disclosure of the fastening 40 and holding means;

Figure 2 is a top plan view of a portion of a double wall construction embodying my invention;

Figure 3 is a top plan view of a portion of 45 a double wall construction embodying my invention, the corner construction being illustrated;

Figure 4 is a sectional view illustrating the particular holding means for the 50 sections.

In carrying out my invention, I provide a plurality of slabs or units 1 which are pre-cast and preferably formed with tongues 2 and grooves 3 on its edges so that the different slabs may interfit. These slabs may be formed of any suitable material and faced

in any desired manner for ornamental and decorative purposes, as is well understood.

They are also provided with the longitudinal metal reinforcing rod 4 which is exposed for a portion 5, of its length, by the cutting out of the recess 6 in one side of the top edge portion of certain slabs or units, as clearly shown in Figures 1 and 4.

In the single wall construction, the slabs are supported by a suitable post 7, which may be precast or cast in situ and is substantially rectangular in horizontal cross section, having the vertical reinforcements 8 near each corner and the horizontal reinforcement 9 extending around the vertical reinforcements and following the sectional conformation of the post. The post is provided with the vertical groove or recess 10 which extends the full length thereof, and at certain intervals corresponding to the recess 6, in the slabs or units, is additionally recessed or cut out as at 11. These additional recesses 11 in the supporting post 7 expose a length 12 of the horizontal reinforcement 9.

In the erection of the single wall, as shown in Figure 1, the exposed portions 12 of the horizontal reinforcement 9 and the exposed portion 5 of the re-inforcement 4 in 80 the slabs or units, are located substantially in alignment, the cut-out portions or recesses 6 and 11, also being in alignment. As the wall is built, the holding members 13, which are shown in the form of a double hook, are 85 secured over the exposed portions of the reinforcing members, and thereby hold the slabs or units to the supporting posts, and thus support the wall. When the erection of the wall is completed or has progressed a 90 sufficient distance, the cement is poured into the vertical groove 10 in the supporting post, completely filling the same, and also the recesses 6 in the slabs or units, and the recess 11 in the supporting posts and completely covering the hook members 13 and the exposed portions of the reinforcements, thereby securely binding the wall together 95 in a unitary structure, and protecting all the metal parts from exposure to the weather 100 and the air, and preventing rust and deterioration of the same from other causes.

It is to be noted that after the cement is poured into the groove 10 and the communicating recesses, and has set, shoulders will 110 be provided on which the slabs or units next above will rest, so that the entire weight of

the superimposed slabs will not be upon the lower ones as they are partially supported on these lugs or shoulders.

The same idea is applicable to the double wall construction, as shown in Figures 2 and 3, where, instead of using the supporting posts, smaller slabs or units 14 of substantially the same construction as the slabs or units 1 are placed between the double arrangement in pairs, each one having the plurality of cut out portions 15 to expose the portions 16 of the reinforcing member. Hook members 17 are utilized to connect these exposed portions 16 of the reinforcing members in the slabs or units 14 and also the exposed portions 5 of the reinforcing members in the slabs or units 1 of the wall. In addition to this, the vertical reinforcements 18 may be used in the angles formed 20 at the intersection of these hook members, and when the wall is completely erected or has progressed sufficiently, cement is poured therein, and, after setting, operates to securely bind and hold the parts together as 25 previously described, in connection with the single wall construction.

The construction shown in Figure 3 is substantially the same as that shown in Figure 2, with the exception that the hook members 30 19 extend from the exposed portions of the reinforcements in the slabs or units 1 to the exposed portions of the reinforcements in the slabs or units 14. Cement is also poured in the space formed by these slabs or units 35 so that a proper supporting column is provided between the walls.

It is therefore seen that I have provided a very simple and effective construction, whereby a wall either single or double, may 40 be quickly erected from pre-cast units and securely held and tied together as an integral structure. The wall is strong and attractive in appearance.

What I claim is:—

45 1. A construction of the character described, including in combination, a plurality of slabs having cut-out portions, an engagement member positioned in said cut-out portions, supporting posts having a vertical groove and also cut-out portions positioned in substantial alignment with the cut-out portions of the slabs and also having an engagement member exposed therein, engaging members engaging corresponding engagement members, and a suitable plastic material disposed in the opening formed by the vertical grooves and said cut-out portions after a wall has been erected.

50 60 2. A construction of the character described, including in combination, a plurality of slabs each having longitudinal reinforcements near one edge and also provided with a cut-out portion forming a recess exposing a portion of the length of said reinforce-

ment, a supporting post having a vertical groove, and also a horizontal reinforcement embedded therein, said supporting post also having a plurality of cut-out portions to provide recesses corresponding to the recesses 70 in said slabs, said cut-out portions of the post exposing lengths of said reinforcements and an engaging member engaging the corresponding exposed lengths of said reinforcements, and a suitable plastic material 75 disposed in the opening formed by said groove and said recesses.

3. A construction of the character described, including in combination, a plurality of slabs each having a cut out portion 80 adjacent one edge, a supporting post having a longitudinal groove and cut-out portions opening into said groove and registering with the cut-out portions of the slabs, and a mass of plastic material cast in said 85 groove and cut-out portions, to form a plurality of shoulders on which said slabs rest.

4. A construction of the character described, including in combination, a plurality of slabs each having a cut-out portion 90 adjacent one edge, a supporting post having a longitudinal groove and cut-out portions opening into said groove and registering with the cut-out portions of the slabs, and a mass of plastic material cast in said 95 groove and cut-out portions, to form a plurality of shoulders on which said slabs rest and means connecting said slabs to said post, said means being embedded in said plastic material. 100

5. A construction of the character described, including in combination, a plurality of slabs, one of said slabs having a cut-out portion opening out of its top edge, a supporting post having a groove and a cut out portion opening into said groove and corresponding to said first mentioned cut out portion, and a mass of plastic material cast in said groove and cut-out portions 105 to form shoulders, one shoulder being within the post and the other shoulder forming a support for the slab next above. 110

6. A construction of the character described, including in combination, a plurality of slabs, one of said slabs having a cut-out portion opening out of its top edge, a supporting post having a groove and a cut out portion opening into said groove and corresponding to said first mentioned cut out portion, and a mass of plastic material cast in said groove and cut-out portions to form shoulders, one shoulder being within the post and the other shoulder forming a support for the slab next above, an engagement member in each cut out portion and an engaging member engaging both engagement members to hold the slabs to the post prior to the casting of the said plastic material, said engaging and engagement members being embedded therein. 115 120 125 130

7. A construction of the character described, including in combination, a plurality of slabs certain of which have a cut out portion adjacent one edge, an engagement member exposed in each cut-out portion, a supporting post having a plurality of cut-out portions corresponding to the cut-out portions in said slabs, an engagement member exposed in each cut-out portion, and an engaging member engaging the corresponding engagement members, a plastic material filling said cut-out portions.

8. A construction of the character described, including in combination, a vertical wall composed of a plurality of slabs, certain of the slabs having a cut-out portion and an engagement member exposed in each cut-out portion, an additional member also provided with cut-out portions, an engagement member positioned in each of said last-mentioned cut-out portions, engaging means adapted to connect engagement members in said slabs and said additional member, a plastic material disposed in said cut-out portions to imbed the engagement means and to form shoulders.

9. A construction of the character described, including in combination, two adjacent members having horizontally aligning recesses, each member having a rigid horizontal reinforcing element therein extending horizontally through the respective recesses, a straight connecting element between said members, the connecting element having a hook at each end fitting in the recesses and engaging over the respective reinforcing elements in said recesses, and a filling material between said members to fill said recesses and to imbed said connecting element.

10. A building construction unit formed of plastic material and having a tongue along one edge and a groove along the opposite edge and also having a longitudinal reinforcement imbedded therein close to one face and adjacent the tongue, said unit having a recess adjacent its tongued edge to expose a part of said longitudinal reinforcement to form an engagement member.

In witness whereof, I have hereunto affixed my hand this 9th day of May, 1918.

FRANK R. HAHN.
